UNITED STATES PATENT OFFICE.

ARSÈNE DION, OF BERKELEY, RHODE ISLAND.

SHUTTLE THREADER BLOCK.

Application filed January 13, 1927. Serial No. 160,977.

The present invention pertains to a novel shuttle threader block designed for insertion in the front end of the shuttle block for looms.

The principal object of the invention is the provision of a device of this character involving a novel construction designed to retain the thread in the block and to prevent it from becoming knotted in the operation of the shuttle. With this object in view the threader block contains a coil adapted to receive the thread, the forward end of the coil being characterized by peculiar formations which prevent escape of the thread except through the usual eye of the device.

The invention is fully disclosed in the following description and in the accompanying drawings in which:

Figure 1 is a plan view of a shuttle equipped with the novel threader block;

Figure 2 is a side elevation thereof;

Figure 3 is a plan view of the shuttle with the threader block removed;

Figure 4 is a section on the line 4—4 of Figure 3;

Figure 5 is a side elevation of the threader block;

Figure 6 is a front elevation thereof;

Figure 7 is a section on the line 7—7 of Figure 6;

Figure 8 is a section on the line 8—8 of Figure 5;

Figure 9 is a developed plan view of the sheet from which the coil is made; and

Figure 10 is a detached perspective view of the coil.

Reference to these views will now be made by use of like characters which are employed to designate corresponding parts throughout.

In Figures 1, 2, 3 and 4 is shown a shuttle block 1 having the usual chamber 2 for receiving the bobbin 3. The forward end of the shuttle has a cavity 4 in advance of the chamber 2 for receiving the shuttle threader block designated in general by the numeral 5. This member has a longitudinal slot 6 communicating with a lower longitudinal recess 7. The two sides 8 and 9 of the threader block, formed by the slot 6, are provided with outwardly curved wings 10 and 11 respectively for facilitating the entrance of the thread 12 into the slot.

To the top of the wing 11 is secured one edge of a sheet member 13, preferably of

metal, the body of which is disposed within the recess 7 and coiled therein as clearly shown in Figure 8. The inner edge of the sheet, lying within the coil, is slanted or curved as at 14 with reference to the axis 60 of the coil as may be seen by comparison of Figures 9 and 10. At the forward end of the coil, this edge has an inwardly extending tongue 15 which forms a notch 16 in conjunction with the edge 14. Directly adjacent and outwardly of the tongue 15, the forward edge of the coil is formed with a forwardly projecting tooth or point 16' which, with the tongue 15, forms another notch 17. Finally, another notch 18 is cut 70 in the forward edge of the coil and lies substantially opposite the notch 17 with respect to the longitudinal axis of the coil.

One side of the threader block is formed with an outlet opening 19 communicating 75 with a slot 20 through which the thread passes in order to enter the outlet. A pair of pins 21 are inserted in the block at opposite sides of the outlet in order to aid in guiding the thread and to prevent undue 80 wear of the wood.

Directly adjacent the outlet opening the threader block is formed with a hook 22 as clearly shown in Figures 5 and 6. The block also has a fin 23 provided at the same 85 side and slightly overlapping the point of the hook as shown in Figure 5. The threader block has an integral stem 24 projecting from its base and adapted for reception in a corresponding recess 25 cut in the base of 90 the shuttle block. Also, the threader block is formed with a transverse aperture 26 for receiving a securing pin 27 having its ends fixed in the sides of the shuttle block.

A pin 28 is bridged across the central cavity of the threader block, directly in advance of the coil and has its midpoint substantially in line with the longitudinal axis of the coil. Another pin 29 extends from the inner wall of the fin 23 to the opposite 100 side of the threader block. This pin lies at a lower level than pin 28 or near the top of the hook 22 as shown in Figures 6 and 7.

After the thread 12 has been passed into the slot 6 it follows a path around the coil 105 until passing beyond the edge 14 and into the interior. It is then drawn over the pins 28 and 29, through the hook 22 and out of the opening 19. When the thread is taut during travel of the shuttle, it is retained by 110

the pin 28 substantially in the axis of the coil as shown in Figure 8.

If the thread has a tendency to work its way out of the coil, it first enters the notch 16 and is retained by the tongue 15. In the event that the thread does pass the tongue it will be held by the tooth 16' in the notch 17. The last notch 18 holds the thread during the first throw of the shuttle or if 10 the thread in some way passes the obstructions 15 and 16. It will be seen in Figure 6 that the thread passes beneath the pin 29 which prevents the thread from rising out of the hook 22. The fin 23, by overlapping the 15 point of the hook, also holds the thread against escaping from the hook.

While a specific embodiment of the invention has been illustrated and described, it is to be understood that various alterations in 20 the details of construction may be made without departing from the spirit of the invention as indicated by the appended claims.

Having thus fully described the invention, what I claim as new and desire to protect 25 by Letters Patent is:—

1. A shuttle threader block having a longitudinal slot and a longitudinal recess communicating with the slot, a coiled member disposed in the recess and having one end secured to one of the walls of said slot, said member having a notch cut in the forward end thereof, said member having its inner edge slanted with reference to the longitudinal axis of the coil, and a tongue projecting inwardly from said edge and disposed at the forward end of the coil.

2. A shuttle threader block having a longitudinal slot and a longitudinal recess communicating with the slot, a hook formed in advance of said slot, a fin projecting from the block and overlapping the point of said hook, a coiled member disposed in the recess and having one end secured to one of the

walls of said slot, said member having a notch cut in the forward end thereof.

3. A shuttle threader block having a longitudinal slot and a longitudinal recess communicating with the slot, a hook formed in advance of said slot, a fin projecting from the block and overlapping the point of said hook, a coiled member disposed in the recess and having one end secured to one of the walls of said slot, said member having a notch cut in the forward end thereof, said member having its inner edge slanted with reference to the longitudinal axis of the coil, and the tongue projecting inwardly from said edge and disposed at the forward end of the coil.

4. A shuttle threader block having a longitudinal slot and a longitudinal recess communicating with the slot, a coiled member disposed in the recess and having one end secured to one of the walls of said slot, said member having a notch cut in the forward end thereof, and a pin bridged across said recess in advance of said coil and having its midpoint substantially in line with the longitudinal axis of the coil.

5. A shuttle threader block having a longitudinal slot and a longitudinal recess communicating with the slot, a hook formed in advance of said slot, a fin projecting from the block and overlapping the point of said hook, a coiled member disposed in the recess and having one end secured to one of the walls of said slot, said member having a notch cut in the forward end thereof, a pin bridged across said recess in advance of said coil and having its midpoint substantially in line with the longitudinal axis of the coil, and another pin disposed at the top of said hook.

In witness whereof I have hereunto set my hand.

ARSÈNE DION.
